UNITED STATES PATENT OFFICE.

THOMAS H. LINDSEY, OF ASHEVILLE, NORTH CAROLINA, ASSIGNEE OF ONE-HALF TO
JAMES K. COWAN, OF ASHEVILLE, NORTH CAROLINA.

PHOTOGRAPHIC-PRINTING MASK.

1,180,513.

Specification of Letters Patent. Patented Apr. 25, 1916.

Application filed April 13, 1915. Serial No. 21,072.

To all whom it may concern:

Be it known that I, THOMAS H. LINDSEY, citizen of the United States, residing at Asheville, in the county of Buncombe and State of North Carolina, have invented certain new and useful Improvements in Photographic-Printing Masks, of which the following is a specification.

This invention relates to improvements 10 in photographic printing masks or machines and is especially useful where the printing is obtained or accomplished through the agency of an artificial light.

An object of the invention is to generally 15 improve structures of this particular type and to embody in a single organization or machine, means for measuring or gaging the size of the photograph prior to the printing thereof; means to positively hold the 20 film or negative and the sensitized paper uniformly in engagement with the exposure glass; means to lock the various adjustable parts in adjusted position; means to make and break the electrical circuit necessary to 25 the production of the mentioned artificial light through manipulation of the pressure-back handle; and means to releasably hold the film against its natural tendency to curl while in the act of printing.

30 The above and additional objects are accomplished by such means as are illustrated in their preferred embodiment in the accompanying drawings, described in the following specification and then more particularly pointed out in the claims which 35 are appended hereto and form a part of this application.

In describing my invention in detail reference will be had to the accompanying 40 drawings wherein like characters denote like or corresponding parts throughout the several views, and in which:—

Figure 1 is a perspective view of my improved photographic printing mask or machine; Fig. 2 is a plan view; Fig. 3 is a cross sectional view, the pressure back being shown in a raised position; Fig. 4 is an enlarged section taken transversely to that of Fig. 3; Fig. 5 is an elevation of the circuit 45 control means; Fig. 6 illustrates the parts shown in Fig. 5 in cross section; and Fig. 7 is a section of the mentioned parts taken at a right angle to that of Fig. 6.

Referring now to the drawings by numerals, 1 designates a suitable frame, pref-

erably rectangular, provided with a correspondingly shaped opening 2 within which the exposure glass 3 is arranged, the top face of the glass being flush with the top face of the frame.

60 A guide strip 4 is affixed to the frame 1 adjacent one of its ends whereby to extend in parallelism therewith, said strip, in conjunction with a retaining strip 5 and a guide pin 6 affording a means whereby the carrier 7 is held against displacement and for sliding movement upon the top face of the frame. The strip 5 is affixed to the guide strip 4 and positioned or arranged to overlap the carrier 7. Pin 6 is affixed to 65 the frame and positioned to operate in a longitudinal slot 8 therefor formed in the carrier in adjacent proximity to the opposite longitudinal edge thereof from that engaged with the guide strip 4. The engagement between the slot terminals and the pin 6 will limit sliding movement of the carrier.

70 That the carrier 7 may be locked against movement subsequent to adjustment 1 provide a guide screw 9, the said screw being affixed to the frame and, like the pin 6, positioned to operate in a slot 10 therefor formed in the carrier, the slot 10 likewise 75 engaged with the carrier 7, the slot 10 affording a means whereby the carrier is held in place. A thumb nut 11 is mounted on the screw 9 and adapted for adjustment, through rotation, into and out of engagement with the carrier whereby to, if desired, lock the carrier against sliding movement. Slots 8 and 10 are preferably alined as shown to advantage in Fig. 2.

80 An L-shaped or right-angled arm 12 is hingedly connected as at 13 to the carrier 7, 85 one end of the angle arm being flush with one end of the carrier, the opposite end however being situated at a point preferably equi-distant from the carrier ends, such arrangement positioning that portion of the arm extending at a right angle to the carrier in such relation to the exposure glass 3 and the top face of the frame 1 as to be moved laterally or transversely thereof through adjustment of the carrier 7. Said 90 arm 12 is normally held in yielding engagement with the mentioned glass and frame through the medium of a leaf spring 14 affixed to the carrier and tensioned to abut the arm at a point adjacent the free end. 95 To raise the arm out of engagement with 100

the glass and frame and against tension of its associated spring, I provide a knob 15, said knob, as shown, being located in such relation to the spring as to in no way interfere therewith. Marginal strips 16 and 17 are fastened in any suitable manner to the under side of the arm 12, the strip 16 extending parallel with the carrier and the strip 17 at a right angle thereto, each strip 10 slightly overlapping the edge of the arm to afford a marginal space upon the photograph or print as will hereinafter more fully appear.

What will be hereinafter referred to as a "pressure-back" is hingedly fastened as indicated at 18 to move bodily with the carrier 7. The pressure-back in its preferred embodiment comprises hingedly connected sections 19 and 20, the former having connection with the carrier as indicated at 18 and spaced therefrom, as shown, to overlap that portion of the arm 12 supporting the marginal strip 16. Section 20 is comparatively large and is hingedly connected 25 as at 21 to the smaller section 19. Marginal strips 16 and 17 not only provide for the formation of a marginal space upon the photograph as pointed out above, but, upon elevation of the arm 12, serve as a means 30 whereby the pressure-back as an entirety is raised or elevated therewith. It will be observed that the pressure back when lowered or horizontally flattened, directly engages with the mentioned strips.

35 A handle 22 for the pressure-back is hingedly connected as at 23 to a suitable block 24 in turn affixed to the carrier 7. Said handle 22 carries, in proximity to the hinge point 23, an abutment block 25, said 40 abutment coöperating with a push button 26 depressible to control the electrical circuits involved. A coil spring 27 is arranged beneath the handle 22 and affixed to the block 24, the terminals of the said spring being 45 adapted to engage the under side of the mentioned handle to at all times exert an upward pressure thereon whereby to maintain the said handle and the pressure-back to which it is connected in an elevated or 50 raised position. The mentioned connection is obtained through the medium of a spring 28 affixed at one end to the handle and at its opposite end to the section 20 of the pressure-back. Handle 22 is further 55 equipped with arcuate leaf springs 29, the terminals of which are adapted to positively engage the top face of the pressure-back to in this manner exert a uniform pressure thereon in the act of printing when 60 handle 22 is lowered. A stop device 30 is fastened to the handle, the said stop being engageable with the top face of the pressure back to increase the pressure thereon and to limit movement of the handle.

65 To receive the wear and tear incident to

long and continued use of the printing mask I provide a metallic strip 31 which, as shown to advantage in Figs. 2 and 3, is fastened to the pressure-back in such relation to the stop device 30 and the springs 29 as to contact therewith when the handle is lowered. Slots 32 are formed in the strip 31, within which slots pins or screws 33 operate, the latter being affixed to the smaller section 19 of the pressure-back whereby to hold the strip 75 against displacement yet permit of slight relative movement occasioned by reason of the hinged connection shown at 21. Strip 31 is of an inherent resilient nature and tensioned to normally maintain section 20 80 of the pressure-back at an acute angle to the section 19, such structure or arrangement permitting the mentioned section to be withdrawn from engagement with the exposure glass without removing the section 20 therefrom. The hinged connection indicated at 21 is so situated with respect to the hinged connection indicated at 23 that the pressure-back when horizontally flattened will automatically position itself to receive the pressure adapted to be directed thereon through forced movement of the handle 22.

Passing on to a detail description of the means utilized to measure or gage the size of the photograph to be printed, the numeral 34 designates a thin metallic strip in the nature of a straight edge positioned at one side of the opening 2 and in parallelism with one of the margins thereof. Said strip is secured to the frame by any suitable means. 100 An adjustable metallic strip 35 is secured to the top of the frame, said last mentioned strip being likewise in the nature of a straight edge and movable bodily longitudinally of the strip 34. Each strip is provided with marginal graduation marks as indicated in Fig. 1. The strip 35 is enlarged at one end as indicated at 36 and provided at its enlarged end with a longitudinal slot 37, said slot with a second slot 105 38 extending parallel therewith affording a guide means whereby the strip is held in place. The free end of the strip 35 is arranged to underlap and operate beneath the strip 34. Slot 38 is formed in a reinforcing strip 39 affixed to the strip 35 at its enlarged end, the reinforcing strip in turn supporting a knob 40 manipulatable to adjust the strip 35 longitudinally of the frame or toward and from the carrier 7. A guide pin 41 is 110 affixed to the frame and operates within the slot 37, while a guide screw 42 is affixed to the frame and operates within the slot 38, the mentioned pin and screw together precluding displacement of the strip 35. A 115 thumb screw 43 is mounted on the screw 42, said thumb screw being manipulatable in a manner common to the art whereby to releasably fasten the strip 35 against movement when adjusted. At each side of the 120 130

frame 1 I dispose a retaining element, the element 44 at one side being fastened at its opposite ends to the frame while the element 44' at the opposite side is fastened to the frame only at one end. Each element is spaced from the frame and is utilizable as will hereinafter appear.

The machine or mask here described and as suggested above is particularly useful where artificial light is utilized as the illuminant. As a means whereby the various lights (not shown) may be switched on or off as occasion demands, I provide an automatic circuit controller designated as an entirety by the numeral 45. The said controller in its preferred embodiment includes in addition to the abutment block 25 and the push button 26 before described, a movable contact device or member 46, said member having connection, by means of a stem 47 with the button 26. The button 26 and the stem 47 operate in a suitable casing 48 therefor, the latter being affixed in any suitable manner within an opening 49 formed in the block 24. A spring 50 is located interiorly of the casing 48 to abut at one end the button 26 and at its opposite end the closed end of the casing, said spring normally maintaining the contact member 46 in engagement with a resilient contact member 51, the latter being arranged exteriorly of the block 24 and affixed to the terminal 52 in turn insulated from the block 24. The engagement of the movable contact 46 with the contact 51 also maintains the latter in engagement with the terminal 53, the double engagement of the said member with the terminals 52 and 53 closing a suitable electrical circuit whereby a colored light is obtained. During the process of printing, the handle 22 is depressed to move abutment 25 into engagement with the button 26, such engagement causing the spring 50 to be compressed and the member 46 moved out of engagement with the contact 51. The latter being constructed of an inherently resilient material, it is evident that the said contact will move out of engagement with the terminal 53, the contact 46 at the same time engaging the terminal 52 and a terminal 54 opposed thereto, the mentioned engagement of the contact 46 with terminals 52 and 54 closing a second circuit whereby to produce a white light of sufficient brilliancy to answer the demand made thereon. The terminal 54 is also insulated from the block to which it is secured.

In operation, the film or negative and sensitized paper are adapted to be arranged in superimposed relation across the exposure opening 2 and upon the top face of the glass, the film or negative, if in the form of a roll, being first arranged to underlap the elements 44, said elements preventing the natural tendency of the film to curl-up

or roll. Next, strip 35 is adjusted relatively to the strip 34, such adjustment determining the length of the photograph to be printed. In Fig. 1 the strip is set to print a photograph four inches in length. Next, arm 12 is laterally adjusted relatively to the strip 35, such adjustment determining the width of the photograph and, as indicated in the said Fig. 1, set to produce a picture four inches in width. The film or negative and the sensitized paper are held in place by the arm 12 and by the tension of the associated spring 14. While the negative is being arranged in the manner described, circuit closing device 45 will operate automatically, through the agency of the spring 50, to close the colored light circuit thereby producing a colored light. After the various adjustable parts have been set as previously mentioned and fastened against displacement, pressure-back 19-20 is lowered or forced into engagement with the paper and film to press the latter firmly and uniformly against the exposure glass. The moment the pressure-back is forced into a final position (horizontal) block 25 will have engaged the button 26 in such a manner as to break the colored light circuit and close the white light circuit thereby creating a clear illuminant necessary to a printing operation. Handle 22 is then maintained in its lowered position until a photograph shall have been completely printed. Spring 27 will elevate the handle immediately upon its release. It is necessary to raise or elevate the arm 12 through manipulation of knob 15 to remove the film after a print has been taken therefrom. The print itself is positioned to engage the top surface of the strips 16 and 17.

From the foregoing, taken in connection with the accompanying drawings it is apparent that photographs varying in size may be printed through adjustment of the arm 12 and the strip 35; that the strips 16 and 17 will produce a marginal white space upon the completed photograph; and that the operation of the circuit closing device is absolutely automatic and such in its nature as to shift the light at the proper moment, it being understood that the light utilized in printing is to be arranged upon the opposite side of the frame from that upon which the mechanism comprising my invention is arranged.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sac-

rificing any of the advantages of my invention, as defined in the appended claims.

Having thus fully described my invention, what I claim as new and desire to secure by Letters Patent, is:—

1. In a photographic printing machine, a frame having an exposure opening formed therein, a carrier slidable transversely of the frame, means affixed to the carrier and movable across the opening to vary the size thereof, means movable toward and from the carrier to vary the size of the opening, a pressure-back movable with the carrier and into and out of engagement with the frame for the purpose specified, and a handle for the pressure-back movable independently thereof.

2. In a photographic printing machine, a frame having an exposure opening formed therein, a carrier mounted for sliding movement upon the frame, guide means for the carrier affixed to the frame, a pressure-back hingedly connected to the carrier and movable into and out of engagement with the frame directly over the mentioned opening, a retaining arm for the negative acted on hingedly connected to the carrier and movable transversely of the frame to vary the size of the opening therein, means adjustable toward and from the carrier to vary the size of the said opening, and a handle hingedly connected to the carrier and having a yielding connection with the pressure-back, the handle being operable to move said pressure-back into and out of engagement with the frame.

3. In a photographic printing machine, a frame having an exposure opening formed therein, a carrier slidable across the frame, means to limit sliding movement of the carrier, guide means for the carrier, a block affixed to the carrier, an arm having a hinge connection with the carrier, the arm being movable therewith and across the opening to vary the size thereof, said arm affording a film retaining means, a pressure-back hingedly connected to the carrier, the said back comprising a pair of hingedly connected sections, means adjustable toward and from the carrier to vary the size of the mentioned opening, an operating handle hingedly connected to the block, and a spring connection between the handle and the pressure-back to move the latter into and out of engagement with the frame, said pressure-back being engageable with the film for the purpose specified.

4. In a photographic printing machine, the combination with a suitable frame having an exposure opening formed therein, of a pressure back comprising hingedly connected sections, a resilient plate having a fixed connection with one of said sections and a loose connection with the other of said sections, said plate being inherently

resilient to normally maintain the section to which it is fixedly connected at an angle to the other of the said sections, and means operable to move the sections and to hold said sections against relative movement.

5. In a photographic printing machine, a frame having an exposure opening formed therein, a carrier movable transversely of the frame, means mounted on the carrier and movable across the opening to vary the size thereof, means movable toward and from the carrier to vary the size of the opening, and a pressure back movable with the carrier into and out of engagement with the frame for the purpose specified.

6. In a photographic printing machine, the combination with a suitable frame having an exposure opening formed therein, of an adjustable carrier, a substantially L-shaped arm hingedly connected thereto, the said arm being movable across the opening to vary the size thereof, means normally maintaining said arm in engagement with the frame to hold the film acted on against displacement, means positioned at each side of the frame to engage the film for the purpose specified means adjustable toward and from the carrier to vary the size of the mentioned opening, and a pressure-back movable into and out of engagement with the frame.

7. In a photographic printing machine, a suitable frame having an exposure opening formed therein, a carrier slidable across the frame, means movable with the carrier to vary the size of the opening, said last mentioned means being substantially L-shaped, one arm of the L-shaped means being arranged in parallelism with one of the opening sides, the other arm of the said L-shaped member being movable toward and from that side of the opening with which it is in parallelism, means movable toward and from the first mentioned arm to vary the size of the opening, said last mentioned means extending in parallelism with the first mentioned arm, marginal strips affixed to the said L-shaped member, and a pressure-back movable relatively to the member into and out of a position closing said opening for the purpose specified.

8. In a photographic printing machine, a carrier, a member movable with the carrier and adjustable across the frame to vary the size of the opening formed therein, a pressure-back affixed to the carrier and movable therewith, means normally maintaining the movable member in engagement with the frame, means to move the pressure-back independently of the adjustable member, and means on the adjustable member adapted for engagement with the pressure-back to move the latter therewith.

9. In a photographic printing machine, the combination with a suitable frame having an exposure opening formed therein, of

a pressure back comprising connected sections, a resilient plate having a fixed connection with one of said sections and a loose connection with the other of said sections, and means operable to move the sections and to hold said sections against relative movement.

In testimony whereof I affix my signature in presence of two witnesses.

THOMAS H. LINDSEY.
